CLAIM

The ornamental design for a VoIP phone, as shown and described.

DESCRIPTION

FIG. 1 is a top, front and right side perspective view of a first embodiment of a VoIP phone showing our new design; FIG. 2 is a bottom, rear and left side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of portion 9 in FIG. 1;

FIG. 10 is an enlarged view of portion 10 in FIG. 2;

FIG. 11 is a top, front and right side perspective view of a second embodiment of the VoIP phone;

FIG. 12 is a bottom, rear and left side perspective view of FIG. 11;

FIG. 13 is a front elevational view of FIG. 11;

FIG. 14 is a rear elevational view of FIG. 11;

FIG. 15 is a left side view of FIG. 11;

FIG. 16 is a right side view of FIG. 11;

FIG. 17 is a top plan view of FIG. 11;

FIG. 18 is a bottom plan view of FIG. 11; and,

FIG. 19 is an enlarged view of portion 19 in FIG. 12.

The even-dash broken lines in the drawings show portions of the VoIP phone that form no part of the claimed design. The dot-dash broken lines are imaginary lines that are included for reference purposes only to identify the enlarged views; the dot-dash broken lines form no part of the claimed design.
